7 Claims. (Cl. 260—627)

This invention relates to the ion-exchange treatment of mixtures of tar acids i. e. phenols, and tar bases i. e. organic nitrogen containing bases, to effect separation and permit recovery of the tar acids in substantially tar base free condition.

This application is a continuation-in-part of our pending application, Serial Number 215,376, filed March 13, 1951, now abandoned, and assigned to the assignee of the present invention.

Tar acids and tar bases are found together in the liquid products of distillation of oil shale and low temperature carbonization of coal and also in the so-called petroleum cresyls produced by the cracking of petroleum. The tar acids are particularly valuable commercially in the production of resins, plasticizers and the like. In such uses their utility is seriously impaired if they are contaminated by tar bases. Unfortunately, the boiling points of the tar acids and the tar bases derived from the above-mentioned sources are such as not to permit their effective separation by distillation. Treatment of the mixtures with strong acids is only partially successful in removing the tar bases and is particularly ineffective for removing those bases which boil above 230° C.

In accordance with this invention, we have found that treatment of a mixture of tar acids and tar bases with a cation exchange resin is extremely effective in removing not only the low-boiling tar bases but also the high boiling tar bases, thereby leaving the tar acids in a substantially tar base free condition.

Furthermore, we have discovered that the capacity of the resin to adsorb the tar bases is commercially satisfactory and also that the resin can be readily and completely regenerated by acid dissolved in a polar solvent in which the tar bases are soluble.

In the afore-mentioned application, the treatment of the mixture of tar acids and tar bases with a cation exchange resin was described as being carried out in a polar solvent. We have since found that the use of a polar solvent is desirable in some cases but not necessary. No solvent at all or a non-polar solvent may be employed. However, the preferred embodiment of the process still includes the use of a polar solvent. One reason for this is the fact that the tar acids and bases are recovered in a solution of a polar solvent e. g. methanol in the separation of tar acids from neutral oil by the countercurrent extractive treatment of tar acid oil with aqueous methanol and hexane as described in the copending application of Gorin and Neuworth, Serial Number 184,474, now U. S. Patent 2,666,796, filed March 13, 1951, and assigned to the assignee of the present invention. There is, therefore, no need to remove the polar solvent before proceeding with the ion exchange treatment. Furthermore, it is sometimes desirable to have a solvent to reduce the viscosity of the feedstock, particularly when high boiling tar acids are present.

Specifically, the preferred method of treatment is as follows. The mixture of tar acids and tar bases is first dissolved in a polar solvent. Examples of such solvents

are methanol, ethanol, propanol, acetone, and methyl ethyl ketone. Preferably the solvent is in an aqueous condition, the amount of water being insufficient to render the tar acids and the tar bases insoluble in the polar solvent.

5 The precise amount of water that may be tolerated varies, of course, with the composition of the tar acids, as well as their concentration, but may easily be determined by simple solubility tests on the mixture. We have found aqueous methanol to be particularly effective.

10 Since the latter solvent is also useful in separating tar acids and tar bases from the neutral oil with which they generally occur in the distillate fractions derived from distillation of coal, oil shale and the like, the resulting extract may be used directly in the present invention.

15 The solution of tar acids and bases is passed through a bed of granular cation exchange resin. Useful agents of this type are the cationic exchange resins containing acidic groups, for example, the sulfonated phenolic-type cation exchanger, the sulfonated coal-type cation exchanger, the sulfonated styrene-type cation exchanger, as well as the corresponding carboxylic cation exchangers.

20 We prefer to use those cation exchange resins which derive their capacity to adsorb essentially from sulfonic acid groups. As a result of contacting the solution of tar acids and bases with the resin, the bases are adsorbed upon the resin and a solution of tar acids substantially free of tar bases is discharged from the bed of resin. The solvent may then be removed by distillation and the tar acids recovered.

25 30 After the cation exchange resin has adsorbed a sufficient quantity of the tar bases, so that it approaches the point at which it will not adsorb any more, or the point at which an appreciable amount of tar bases appears in the effluent, the resin is eluted, preferably by a strong acid such as hydrochloric or sulfuric in a polar solvent in which the tar bases are likewise soluble. While the solvent may advantageously contain some water, the amount of water must not be sufficient to prevent the bases from being completely dissolved; or the capacity

35 40 of the resin to adsorb in subsequent cycles of treatment will be seriously impaired. The polar solvent may be the same polar solvent selected for the base adsorption treatment and is again preferably aqueous methanol. As a result of the elution of the resin, an extract containing the tar bases in the form of their mineral acid salts together with free acid is obtained. The tar bases may readily be recovered from this extract by decomposing the salts with strong alkali followed by distillation. In contrast to the optional use of a polar solvent in the

45 50 treatment of the feedstock with the resin, the use of a polar solvent in the regeneration of the resin is critically essential. Attempts to remove the adsorbed bases without the polar solvent were unsuccessful.

55 The relative concentrations of tar acids and tar bases in the original solution do not appear to be critical in the successful practice of our invention. In general, however, the tar bases are present in a very small amount as compared with the tar acids, i. e. up to about 2.0% of the total tar acids.

60 65 In the following table are tabulated the data obtained by treating a mixture of tar acids and tar bases derived from the distillation of bituminous coal at about 850° F. with sulfonated cation exchangers. Runs 1 and 2 employed a sulfonated phenolic type resin sold under the trademark "Amberlite IR-100" by Resinous Products and Chemical Company. Run 3 employed a sulfonated coal resin sold under the trademark "Zeo-Karb" by the Permutit Company. In all three runs, the mixture of tar acids and tar bases were dissolved in 70% aqueous

70 methanol (i. e. 70 parts by volume of CH_3OH and 30 parts by volume of water). Likewise, in all three runs

the resin was regenerated by a solution of 4% HCl in 70% aqueous methanol.

TABLE
Removal of tar bases by cation exchange resins

Run No.	Feed Solution		Effluent		Resin Capacity ¹
	Percent Tar Bases	Percent Tar Bases in Tar Acids	Percent Tar Bases	Percent Tar Bases in Tar Acids	
1.....	0.15	1.02	0.003	0.02	0.034
2.....	0.07	0.52	0.006	0.04	0.036
3.....	0.18	0.80	0.007	0.07	0.036

¹ Resin capacity calculations have been made on effluents at break through point.

The following example illustrates the application of our process to a mixture of tar acids and bases without the use of a solvent. A mixture consisting of 99.78% by weight of tar acids and 0.22% by weight of tar bases was passed over a sulfonated phenolic type resin sold under the trademark "Amberlite IR-120" by Resinous Products and Chemical Company. The effluent tar acids contained 0.07% by weight of tar bases. The regeneration of the resin is accomplished in the same manner as described above.

According to the provisions of the patent statutes, we have explained the principle, preferred construction, and mode of operation of our invention and have illustrated and described what we now consider to represent its best embodiment. However, we desire to have it understood that, within the scope of the appended claims, the invention may be practiced otherwise than as specifically illustrated and described.

We claim:

1. The method of removing contaminating quantities of tar bases from a mixture consisting essentially of tar acids and tar bases derived from low temperature carbonization tar which comprises continuously passing said mixture in intimate contact with a cation exchange resin whereby said tar bases are adsorbed on said resin and said tar acids are passed therethrough, continuously collecting the effluent liquid which has passed through said cation exchange resin, said effluent liquid containing tar acids substantially free of tar bases, until said resin becomes substantially saturated with tar bases, thereafter regenerating said resin by passing therethrough a solution of strong acid in an aqueous polar solvent selected from the class consisting of methanol, ethanol, propanol, acetone and methyl ethyl ketone to desorb said tar bases from said cation exchange resin, recovering said solution of strong acid in an aqueous polar solvent containing desorbed tar bases, and repeating the entire process in cyclic fashion.

2. The method of removing contaminating quantities of tar bases from a mixture consisting essentially of tar acids and tar bases derived from low temperature carbonization tar which comprises preparing a solution of said mixture in a polar solvent selected from the class consisting of methanol, ethanol, propanol, acetone and methyl ethyl ketone, continuously passing said solution in intimate contact with a cation exchange resin whereby said tar bases are adsorbed on said resin and whereby said tar acids and polar solvent are passed therethrough, and continuously collecting the effluent liquid which has passed through said cation exchange resin, said effluent liquid containing tar acids substantially free of tar bases dissolved in said polar solvent, until said resin becomes substantially saturated with tar bases, thereafter regener-

ating said resin by passing therethrough a solution of strong acid in an aqueous polar solvent selected from the class consisting of methanol, ethanol, propanol, acetone and methyl ethyl ketone to desorb said tar bases from said cation exchange resin, recovering said solution of strong acid in an aqueous polar solvent containing desorbed tar bases, and repeating the entire process in cyclic fashion.

3. The method according to claim 2 in which the tar bases comprise tar bases boiling above 200° C.

4. The method according to claim 2 in which the cation exchange resin is one which derives its exchange capacity essentially from acid groups.

5. The method according to claim 2 in which the cation exchange resin is one which derives its exchange capacity essentially from sulfonic groups.

6. The method of removing contaminating quantities of tar bases from a mixture consisting essentially of tar acids and tar bases derived from low temperature car-

bonization tar which comprises preparing a solution of said mixture in a polar solvent selected from the class consisting of methanol, ethanol, propanol, acetone and methyl ethyl ketone, continuously passing said solution in intimate contact with a cation exchange resin whereby said tar bases are adsorbed on said resin and whereby said tar acids and said polar solvent are passed therethrough, continuously collecting the effluent liquid which has passed through said cation exchange resin, said effluent liquid containing tar acids substantially free of tar bases,

dissolved in said polar solvent until said resin becomes substantially saturated with tar bases, thereafter regenerating said resin by passing therethrough a solution of strong acid in aqueous methanol to desorb said tar bases from said cation exchange resin, recovering said solution of strong acid in aqueous methanol containing desorbed tar bases, and repeating the entire process in cyclic fashion.

7. The method of removing contaminating quantities of tar bases from a mixture consisting essentially of tar acids and tar bases derived from low temperature car-

bonization tar which comprises preparing a solution of said mixture in a polar solvent selected from the class consisting of methanol, ethanol, propanol, acetone and methyl ethyl ketone, continuously passing said solution in intimate contact with a cation exchange resin whereby said tar bases are adsorbed on said resin and whereby said tar acids and said polar solvent are passed therethrough, continuously collecting the effluent liquid which has passed through said cation exchange resin, said effluent liquid containing tar acids substantially free of tar bases

dissolved in said polar solvent, until said resin becomes substantially saturated with tar bases, thereafter regenerating said resin by passing therethrough a solution of strong acid selected from the class consisting of sulfuric acid and hydrochloric acid, in aqueous methanol to desorb said tar bases from said cation exchange resin, recovering said solution of strong acid in aqueous methanol containing desorbed tar bases, and repeating the entire process in cyclic fashion.
